UNITED STATES PATENT OFFICE.

JOSEPH F. PUNZAK, OF BROOKLYN, NEW YORK, ASSIGNOR TO DAVID H. ZELL, INC.,
OF NEW YORK, N. Y., A CORPORATION OF NEW YORK.

DESIGN FOR A COIN BANK.

Application filed June 14, 1924. Serial No. 9,872. Term of patent 3½ years.

To all whom it may concern:

Be it known that I, JOSEPH F. PUNZAK, a citizen of the United States, and a resident of Brooklyn, county of Kings, and State of New York, have invented a certain new original, and ornamental Design for a Coin Bank, of which the following is a specification reference being had to the accompanying drawing, forming part thereof.

In the drawing:

I claim—

The ornamental design for a coin bank, as shown.

JOSEPH F. PUNZAK.
